CLAIM

The ornamental design for a countertop oral irrigator, as shown and described.

DESCRIPTION

FIG. 1 is a perspective view of a countertop oral irrigator showing the claimed design;

FIG. 2 is a top plan view thereof;

FIG. 3 is a left side view thereof;

FIG. 4 is a front elevational view thereof;

FIG. 5 is a right side view thereof;

FIG. 6 is a rear elevational view thereof; and

FIG. 7 is a bottom plan view thereof; and,

FIG. 8 is a close-up view of a portion of the countertop oral irrigator as circled in FIG. 6.

The broken lines illustrate portions of the countertop oral irrigator that form no part of the claimed design.
